CLAIM

The ornamental design for a beverage carton having detachable coasters, as shown and described.

DESCRIPTION

FIG. 1 is an isometric view of a beverage carton having detachable coasters, showing my new design;

FIG. 2 is a top plan view thereof; the bottom plan view being a mirror image thereof;

FIG. 3 is a front elevation thereof;

FIG. 4 is a left side elevation thereof; the right side elevation being a mirror image thereof; and,

FIG. 5 is a rear elevation thereof.

The broken line showing on FIGS. 1 & 2 represent perforation lines defining the perimeter of the punch-out coasters.
